COIN CONTROLLED TIMING MECHANISM

James M. Curless, Chicago, Ill., assignor to Automatic Refrigerator Corporation, Chicago, Ill., a corporation of Delaware

Application October 17, 1930, Serial No. 489,287

8 Claims. (Cl. 194—9)

This invention has for its object the provision of a new coin-controlled timing mechanism which is simple, compact, inexpensive, accurate and dependable.

5 While the foregoing statement is indicative in a general way of the nature of the invention, other more specific objects and advantages will be apparent upon a full understanding of the construction, arrangement and operation of the improved mechanism.

In order that the invention may be readily understood, one embodiment of the same is presented herein, but it will of course be appreciated that such embodiment is intended primarily by way of exemplification, and that the invention is capable of incorporation in other forms coming equally within the scope of the appended claims.

In the accompanying drawings:

Fig. 1 is a front view of the mechanism, showing the cover plate of the casing removed and the main switch in its closed position;

Fig. 2 is a horizontal section through the casing, taken on the line 2—2 of Fig. 1;

Fig. 3 is a vertical section through the casing, taken on the line 3—3 of Fig. 1;

Fig. 4 is an enlarged vertical section through certain parts of the mechanism, taken on the line 4—4 of Fig. 1;

Fig. 5 is a fragmentary front view of the cover plate at the location of the observation window; and

Fig. 6 is a fragmentary front view of the mechanism, corresponding to the central portion of Fig. 1, showing the main switch in its open position.

The coin-controlled timing mechanism of the invention is compactly housed within a generally rectangular casing 10. The casing is open at the front and is provided with a cover plate 11 which is removably held in position by a lock 12.

The apparatus includes an electric timing motor 13 of ordinary construction which is attached to the rear face of a vertical partition 14 in the casing. The armature shaft of the motor 13 is connected by reduction gearing with a slow speed shaft 15 which projects forwardly through an aperture 16 in the partition (see Fig. 1). The reduction gearing is of ordinary construction and is enclosed within a gear case 17 which is positioned between the motor and the partition.

The shaft 15 is provided on its front end with a small pinion 18 which meshes upwardly with a larger pinion 19. The pinion 19 is journaled on a stub shaft 20 and is provided at its rear face with a small pinion 21 (see Fig. 2) which

meshes with a relatively large gear 22. The gear 22 is journaled on another stub shaft 23 and is provided at its front face with a small pinion 24. The pinion 24 meshes laterally with an arcuately movable planet pinion 25 which is journaled on the outer end of one arm 26 of a bell-crank lever 27. The lever 27 is pivotally mounted on the front end of the shaft 23. The planet pinion 25 also meshes laterally with a relatively large gear 28 (see Fig. 4) which is journaled on a rod 29 which projects forwardly from the partition.

The free end of the arm 26 of the bell-crank lever is yieldingly maintained in a downwardly inclined position during the rotation of the motor 13 by a tensioned coil spring 30 which extends from a stationary hook 31 to the free end of the other arm 32 of the bell crank lever. When the motor 13 rotates, the gear 22 rotates very slowly in a clockwise direction, and the gear 28 rotates even more slowly in a clockwise direction, the rotation of the gear 28 being due to the anchorage provided for the planet pinion 25 by the resistance of the spring 30.

The gear 28 is provided with a forwardly projecting sleeve 33 on which an escapement wheel 34 is journaled. The wheel 34 is torsionally connected to the gear 28 by a light coil spring 35 which encompasses the sleeve and is attached at one end to the wheel and at the other end to the sleeve. The wheel 34 is provided on its rear face with a rearwardly projecting stud 36 which is disposed in the path of revolution of a similar stud 37 on the front face of the gear 28. The spring 35 is so arranged as to tend to rotate the wheel in a clockwise direction after the gear 28 has been rotated in a clockwise direction with the wheel held against such movement.

The escapement wheel 34 is normally held against clockwise rotation by an escapement pawl 38 which is pivotally attached to a pin 39. The pawl 38 has a nose 40 which is normally held by a tensioned coil spring 41 in a position behind one of several teeth 42 on the periphery of the wheel. When the pawl 38 is oscillated in a clockwise direction, the nose 40 on the pawl will release from the tooth 42 which it previously engaged, and another nose 43 on the pawl will move into the path of such tooth, whereby to permit the wheel 34 to rotate in a clockwise direction under the action of the spring 35 through a short arc corresponding to the distance between adjoining teeth.

The escapement pawl 38 is oscillated in a clockwise direction under certain conditions by means of a solenoid 44. The core 45 of the solenoid 55

is connected to the pawl by a link 46. The solenoid is energized to exert a pull on the link 46 whenever a coin, such as a twenty-five cent piece, is caused to drop through a vertically extending slot 47 which is formed in a portion of a coin-receiving device 48. The coin is first inserted in an apertured slide 49 of ordinary construction, which slide, when pushed in, will allow the coin to drop into a hopper 50 at the upper end of the slot 47.

As the coin passes downwardly through the slot 47, it depresses a light finger 51 (see Fig. 3) which extends across the slot. The finger 51 is pivoted at 52 to a rearwardly projecting portion 53 of the device 48 and is provided with a cam 54 which acts, when the finger is depressed, to force a spring contact member 55 against a normally spaced spring contact member 56. The contact members 55 and 56 are arranged in the electrical circuit of the solenoid 44, and, as a result, the solenoid is energized, causing the pawl 38 to permit the wheel 34 to turn in a clockwise direction under the action of the wound spring 35 through one-ninth of a revolution, there being, in the particular construction shown, nine teeth on the wheel. If desired, several coins may be inserted at the same time, one after the other, the wheel 34 turning one-ninth of a revolution for each coin inserted.

Before the insertion of the first coin, the stud 37 on the gear 28 will be in a position in abutment with the stud 36 on the wheel 34. After the first coin has been inserted, however, the stud 36 will have been moved by the wheel into a position wherein the gear 28 will have to rotate through one-ninth of a revolution before the stud 37 will abut again with the stud 36. If several coins, for instance four, have been inserted at the same time, the stud 36 will have assumed a position wherein the gear 28 will have to rotate through four-ninths of a revolution before the stud 37 will abut with the stud 36.

As previously stated, the gear 28 rotates very slowly in a clockwise direction when the motor 13 is operating. When the stud 37 on the gear 28 finally comes into engagement with the stud 36 on the wheel 34, the gear 28 will be prevented from rotating any farther, and the planet pinion 25, which is in mesh with the gear 28, will thereupon commence to travel upwardly in an arc. The upward movement of the pinion 25 will of course impart a corresponding oscillation to the bell-crank lever 27, the latter moving from the position shown in Fig. 1 to the position shown in Fig. 6.

The bell-crank lever 27 is connected by a link 57 to a throw-over lever 58 which is pivoted at 59 to a stationary bracket 60. An arm 61 is pivoted at 62 to the lower portion of the lever 58 and is provided at one end with a roller 63 for coaction with either one of two beveled faces 64 and 65 on the lower pointed end of a plate 66. The plate 66 is pivoted at 67 to the bracket 60 and forms a tiltable support for a mercury switch 68 of ordinary construction. The switch 68, which consists of a glass capsule partly filled with mercury, is attached to a forwardly extending portion of the plate 66 by a pair of resiliently expansible clamps 69. The roller 63 is pressed upwardly against either the edge 64 or the edge 65 of the tiltable plate 66 by means of a tensioned coil spring 70 which is attached at its lower end to the arm 61. The spring 70, acting through the roller 63 on one of the inclined cam edges of the plate 66, serves to hold the

plate, and consequently the switch 68, in either position into which the same is tilted.

When the bell-crank lever 27 moves into the position shown in Fig. 6, it will oscillate the throw-over lever 58 in a clockwise direction, causing the roller 63 to ride under the lower tip of the plate 66 and cam the plate into the tilted position shown in Fig. 6, thereby tilting the switch 68 into its open position. The switch 68 is in the circuit of the motor 13.

The switch 68 will remain in its open position until another coin is inserted. Upon insertion of another coin, the stud 36 on the wheel 34 will move ahead of the stud 37 out of the way of the latter. The tendency of the thus released gear 28 to rotate under the stored up energy of the spring 35 will move the planet gear 25 downwardly, thereby oscillating the bell-crank lever 27 in a counterclockwise direction, and such movement of the bell-crank lever will cause the throw-over lever 58 to oscillate in a counterclockwise direction, riding the roller 63 from the cam edge 64 to the cam edge 65 and resulting in the switch 68 being tilted into its closed position.

In the particular mechanism shown, the motor 13 will start up when a twenty-five cent piece is inserted and will operate continuously for 40 hours, stopping automatically at the end of that period. If more than one twenty-five cent piece, for instance four, are inserted at the same time, the motor will start up and will operate 160 hours before stopping. In order to indicate how long the motor will run on coins previously inserted, it is merely necessary to look through an observation window 11 in the front cover plate 11 and notice the position of a pointer 72 with respect to a series of numerals which are arranged in a circle on the front face of the escapement wheel 34. The numerals commence with "0" and run up to "8", covering the nine different positions of the escapement wheel. After the motor is automatically stopped, the pointer will indicate "0". In that position of the pointer, the stud 37 on the control gear 28 will of course be in abutment with the stud 36 on the escapement wheel. When one coin is inserted to start the motor, the pointer 72 will indicate "1". If several coins, for example four, are inserted at about the same time, the pointer will indicate "4". As the forty-hour periods of time are successively used up, the pointer will turn slowly back around the scale in a clockwise direction, indicating accurately at any time the number of forty-hour periods which the motor still has to run.

The coin-controlled timing mechanism of the invention may be used for a great many different purposes, the switch 68 being intended for inclusion in the circuit of an associated electrical device. A particularly valuable adaptation of the mechanism, in novel cooperation with electrical refrigeration apparatus, is disclosed in an application for patent filed by Jack K. Butler on even date herewith.

I claim:

1. In a coin-controlled timing mechanism, the combination with a switch for use in operating an associated device, of a constant speed electric motor in a circuit controlled by the switch, coin-actuated means for closing the switch, a train of reduction gears connected with the motor, a planet gear in mesh with one of said gears, a control gear in mesh with the planet gear, stop means for stopping the control gear after it has turned through a predetermined angle whereby to cause planetary movement of the planet gear, 75

means for positioning said stop means with reference to said control gear, and means actuated by such planetary movement for opening the switch.

- 5 2. In a coin-controlled timing mechanism, the combination with a switch for use in operating an associated device, of a constant speed electric motor in a circuit controlled by the switch, coin-actuated means for closing the switch, a train 10 of reduction gears connected with the motor, a planet gear in mesh with one of said gears, a control gear in mesh with the planet gear, an adjustably positioned stop for arresting the control gear after it has turned through a predetermined angle whereby to cause planetary movement of the planet gear, means supplementary to said coin-actuated means for positioning said stop with reference to said control gear in accordance with the coins inserted, and means actuated by such planetary movement for opening the switch.

- 15 3. In a coin-controlled timing mechanism, the combination with a switch for use in operating an associated device, of a constant speed electric motor in a circuit controlled by the switch, coin-actuated means for closing the switch, a train 20 of reduction gears connected with the motor, a planet gear in mesh with one of said gears, a control gear in mesh with the planet gear, an 25 adjustably positioned stop for arresting the control gear after it has turned through a predetermined angle whereby to cause planetary movement of the planet gear, means actuated by such planetary movement for opening the switch, and means for changing the position of the stop.

- 30 4. A timing mechanism of the character described comprising a constant speed electric motor, a speed reducing gear train driven by the motor, an escapement wheel associated with one of the gears of the gear train, a tiltable mercury switch for controlling operation of the motor, means connecting the switch with the gear train for tilting the switch in response to predetermined operations of the gear train, and 35 means including a coin-operated circuit breaker controlling movement of the escapement wheel with respect to its associated gear to predetermine the time operating period of the mechanism.

- 40 5. In coin-controlled timing means, in combination with a switch for use in controlling operation of an associated mechanism, a constant speed electric motor, a train of reduction gears connected with the motor, a lever pivoted for 45 movement about the axis of one of the gears of said gear train, a planet gear rotatably mounted on said lever and driven by said one gear, a control gear meshing with said planet gear, a stop for arresting said control gear whereby to cause 50 planetary movement of said planet gear and movement in one direction of said lever, means for opening said switch upon movement of said lever in said direction, coin-actuated means for

55 effecting movement of said lever in the opposite direction and closing of the switch upon insertion of a coin, said coin-actuated means being adapted for reception of a plurality of coins inserted one immediately after the other, and means supplementary to said coin-actuated means for positioning said stop with reference to said control gear in accordance with the number of coins inserted.

6. In coin-controlled timing means, in combination with a switch for use in controlling operation of an associated mechanism, a constant speed electric motor, coin-actuated means for closing the switch, a train of reduction gears 10 connected with the motor, a planet gear driven by said gear train, a control gear in mesh with the planet gear, an adjustably positioned stop for arresting the control gear after it has turned through a predetermined angle whereby to cause planetary movement of the planet gear, means 15 actuated by such planetary movement for opening the switch, and means for changing the position of the stop.

20 7. In coin-controlled timing means, in combination with a switch for controlling operation of an associated mechanism, a constant speed electric motor, a movable leading element, coin controlled mechanism for advancing said element a predetermined distance in one direction for each 25 coin inserted, said mechanism being adapted for reception of a plurality of coins inserted one immediately after the other with corresponding advancement of said element, a movable following element, means effective for continuously driving said following element from said motor in 30 the same direction as said leading element and without interruption during insertion of coins, means for opening said switch when said following element overtakes said leading element, and means for closing said switch upon the insertion of a coin.

35 8. In a coin-controlled timing means, a casing, a switch therein for controlling operation of an associated mechanism, a partition within said casing, a constant speed electric motor supported 40 at the rear of said partition, a movable leading element at the front of said partition, coin-controlled mechanism for advancing said element a predetermined distance in one direction for each coin inserted, said mechanism being adapted for 45 reception of a plurality of coins inserted one immediately after the other with corresponding advancement of said element, a movable following element at the front of said partition, means effective for continuously driving said following 50 element from said motor in the same direction as said leading element and without interruption during insertion of coins, means for opening said switch when said following element overtakes said leading element, and means for closing said 55 switch upon the insertion of a coin.

JAMES M. CURLESS.
